FRANCIS MONIER, OF NEUILLY-SUR-SEINE, FRANCE

CARBURETOR FOR INTERNAL-COMBUSTION ENGINES

Application filed October 31, 1922, Serial No. 598,084, and in France November 5, 1921.

My invention relates to carburetors where-
in the feed of the liquid fuel, gasoline for in-
stance, is produced by the suction of the en-
gine and the flow of air around or past a fuel
feed or spray nozzle, the flow being regulated
5 by opening or closing a throttle valve in the
engine suction conduit. In ordinary types
of carburetor this flow of air which is nil
when the valve is closed, increases in propor-
tion to the opening, whilst the reduction of
10 pressure which acts between the motor and
this valve is very great when the valve is
closed, and decreases in proportion to the
opening, so as to fall to the value of the reduc-
tion due to the rate of flow of air when the
15 valve is fully open.

If the reduction of pressure, on the con-
trary, could be increased in proportion to the
opening of the valve, the suction and diffusion
20 of the fuel may then be produced directly by
this reduction and a perfect carburation may
be obtained.

The object of the present invention is to
effect a suction and feed of the liquid fuel
25 exactly according to the depression produced
by the engine itself at all times or with all
openings of the throttle or, in other words,
in such manner that the suction depression
30 acting on the spray nozzle shall increase with
the opening of the throttle valve and the fuel
feed due to suction shall vary automatically
in proportion to the engine speed.

According to my present invention the feed
of the liquid fuel by suction at any time re-
35 sults from the difference between two depre-
sions exerted by the engine upon the liquid
fuel contained in a suitable fluid-tight tank,
or reservoir, for example, a float feed tank,
said two depressions being produced in the
40 carburetor on the engine side of the butter-
fly or throttle valve and acting respectively,
one upon a spray nozzle or opening deliver-
ing the fuel into the air conduit or Venturi
tube and the other acting at any point in said
45 conduit or tube upon the outlet of a pipe con-
nected with the air space above the body of
fluid and with a depression effect less than
that exerted on the spray nozzle. In this ar-
rangement the amount of fuel drawn in will
50 depend upon the difference between the two

depressions, said difference varying directly
with the speed and suction of the engine and
increasing with the speed.

Fig. 1 is a vertical section through a car-
buretor embodying my invention.

Fig. 2 is a horizontal section through the
same taken on line 2—2 of Fig. 1.

Fig. 3 is a vertical section taken through
the diffuser on the line 3—3 of Fig. 2.

Referring now to a typical construction of
apparatus in which my invention may be em-
bodied for practical use and illustrated in
Figs. 1, 2, and 3, a diffuser or venturi is shown
at 13 having an air tube 11 opening into the
same at the pre-selected position above the
spray nozzle by the outlet 11^a and connected
through piping, as shown, with the space
above the liquid in the float chamber 1 formed
in the casing 52 and having the usual or suit-
able float 56 for maintaining the level of liq-
uid therein. The diverging cone 13 into
which 11^a opens meets at the smaller end
thereof a converging cone 12, the two cones
being secured together in any desired manner
in the carburetor casting or body. The an-
nular passage 14 forming with the body of
the carburetor an annular chamber 16, com-
municates with the body of liquid in the float
chamber by a pipe 5 opening at 8 into the
chamber 16 and the feed of the fuel takes
place through the annular passage 14, the fuel
being mixed with the air delivered in the
usual way into the lower end of the double
diffuser or venturi from the chamber 57 sup-
plied with air through the opening 58. The
fuel passes to duct 5 through the guide rod
for the float 56, as clearly shown, or may be
otherwise supplied thereto. The lower portion
of chamber 16 communicates with the
air passageway by means of ducts 17 to per-
mit rapid discharge of accumulated fuel from
this chamber when the ducts are uncovered
as described below.

The throttle valve operated by arm 22 or
otherwise is adapted to close more or less the
opening through which air is delivered to the
venturi and may be of any desired form. By
preference I use a cone-shaped member 19
mounted in the valve chamber 57 and mov-
able axially on the element 42 and co-operat-
100

ing with the narrow part of the diffuser cones or venturis to govern the flow under the engine suction. By using this form of valve an increased or stronger draft of air may be caused to pass the spray nozzle or annular opening 14 when the valve is nearly closed by entering the restricted portion of the venturi or diffuser. This compensates for the diminution of the effective depression at the spray nozzle due to the diminution of suction when the flow of air through the Venturi tube is nearly shut off, the tendency then being towards a close equalization of the depressions and little difference of depression effective in sucking the fuel. When however the throttle valve is open, the depression at 14 is necessarily greater than at 11^a because the draft of air is stronger in the restricted part of the venturi than in the diverging part. I do not limit myself however to the particular details of throttle valve shown.

The action in effect results from the fact that when the throttle valve 19 is closed or nearly closed it enters the restricted portion of the Venturi tube or the throat of the suction tube and causes an increased draft of air to pass the spray nozzle formed in some cases by the annular opening 14 located between the reverse cones forming sections of the Venturi tube. This strong draft of air insures by its dynamic effect a greater suction upon the fuel emerging from the spray nozzle.

When the throttle valve is open the depression acting at 14 is nevertheless greater than at the depression orifice or opening 11^a owing to the fact that the spray nozzle is at the restricted part of the Venturi tube where the draft or depression is stronger than in the diverging part where the air outlet 11^a is located. In previous types of carburetor employing difference of depression to effect the feed of the fuel, the apparatus works imperfectly for slow running motor because a type of valve of the ordinary construction is employed and when it is closed or nearly closed the depression will be practically the same for the two depression elements, being in effect the static depression. In this condition of the usual valve no effective dynamic depression or effect exists on the spray nozzle since the draft of air owing to the closure of the throttle, is at such time very small in the suction tube.

The depression in the chamber 16 may be varied by means of a needle valve 44 controlling an air inlet opening 43 which normally admits a very small portion of outside air for adjusting the relative depressions at 11^a and 14.

60 The closure member 26 is adapted to close the openings 17 and as indicated for example in Fig. 2, this member is held in elevated position by means of the compression spring 27, shown in Fig. 2, so that the openings 17 are normally closed before the valve 19

reaches closed position. The closure 26 is formed with vertical transverse openings 29 to permit the passage of air past the closure 26 after the latter has closed the openings 17. The closure 26 and throttle valve 19 are supported upon a vertical post 42, the closure 26 being slidably mounted upon an extended shank of the valve member 19. This shank is formed with oppositely extending fingers 23 engaged by the forked ends of the controlling arms 20 which together with the operating arm 22 are mounted upon the transverse rotatable shaft 21.

It will thus be seen that movement of the arm 22 causes a corresponding movement of the throttle valve 19 and the closure 26.

In the operation of the apparatus when the throttle is wide open, the suction of the motor produces at the outlet 11^a positioned in accordance with the principle hereinbefore described, a rapid air flow which produces a reduction of pressure in the space above the fluid in the reservoir. The suction of the motor also produces a reduction of pressure at the outlet of the tube 5 and this reduction, owing to the more rapid flow, will be greater than that at the outlet 11^a and will act on the fuel enclosed in the reservoir on the surface of which the pre-selected weaker reduction produced by 11^a acts. The amount of fuel supplied is then determined by the difference of these two reductions while the valve is opened and the motor is running. If now, to reduce the speed of running the motor, the throttle valve is closed, the motor sucks directly unequally at the outlets 11^a and 8, and the difference of the two reductions is very small corresponding to an amount of fuel proportional to the speed of the greatly reduced running of the motor. For the intermediate positions of the throttle valve the difference of the two reductions will gradually diminish corresponding to a smaller amount of fuel proportionate to the speed of running of the motor. The extent of the difference of depression is determined by properly selecting the position of the outlet 11^a with reference to the fuel outlet to secure the desired proportions of fuel and air desired for a normal running at the various positions of opening of the throttle.

Claims:

1. In a carburetor for an explosion engine, the combination of a reservoir partly filled with liquid fuel, a pipe through which fuel can be sucked into the engine and mixed with air and formed with zones of greater and less constriction, a tube opening at one end beneath the level of the liquid in the reservoir and terminating at the other end in a plurality of openings extending into the more constricted zone of said pipe and spaced longitudinally of said pipe, a second tube opening at one end into the reservoir above the level of the liquid and at the other end

into the less constricted zone of said pipe and a throttle valve in the pipe operable outwardly of the opening thereinto of both said tubes, said throttle valve including portions movable gradually toward or from position to close certain of the openings of said first-named tube into said intake pipe as said throttle valve is moved toward closed or open position respectively.

10 2. In a carburetor for an explosion engine, the combination of a reservoir partly filled with liquid fuel, a pipe through which fuel can be sucked into the engine and mixed with air and which has portions of greater and less constriction, a fuel inlet chamber formed with upper and lower openings, opening into said pipe at and near the portion of greater constriction respectively, a tube opening at one end beneath the level of the liquid in the 20 reservoir and at the other end in said chamber, a throttle valve movable toward or from said openings for producing closed and open throttle conditions respectively, means controlled in conjunction with said throttle for 25 closing said lower opening as said throttle is moved toward closed position but before closed throttle condition is reached, and for maintaining said openings closed until said throttle is moved toward open throttle condition and a second tube opening at one end 30 into the reservoir above the level of the liquid and at the other end into the pipe inwardly of the more constricted portion thereof.

In testimony whereof I affix my signature.

FRANCIS MONIER.
